UNITED STATES PATENT OFFICE

143,790

DESIGN FOR A BRACELET OR SIMILAR ARTICLE

Alice Spalding Bowen, Honolulu, Territory of Hawaii, assignor to S. & S. Gump Co., a corporation of California

Application August 28, 1945, Serial No. 121,676

Term of patent 14 years

(Cl. D45—4)

To all whom it may concern:

Be it known that I, Alice Spalding Bowen, a citizen of the United States, residing at the city of Honolulu, territory of Hawaii, have invented a new, original, and ornamental Design for a Bracelet or Similar Article, of which the following is a specification, reference being had to the accompanying drawing, forming a part thereof.

In the accompanying drawing:

Fig. 1 is a perspective view of a bracelet or similar article showing my new design;

Fig. 2 is a top edge view thereof; and

Fig. 3 is a top plan view of the bracelet or similar article in an extended position.

I claim:

The ornamental design for a bracelet or similar article, substantially as shown.

ALICE SPALDING BOWEN.
